United States Patent Office.

FRANCIS GREENE, OF TROY, PENNSYLVANIA.

Letters Patent No. 79,466, dated June 30, 1868.

IMPROVEMENT IN DOOR-KEYS.

The Schedule referred to in these Letters Patent and making part of the same.

TO ALL WHOM IT MAY CONCERN:

Be it known that I, FRANCIS GREENE, of Troy, in the county of Bradford, and State of Pennsylvania, have invented a new and useful Improvement in Keys; and I do hereby declare that the following is a full, clear, and exact description thereof, reference being had to the accompanying drawings.

The nature of my invention consists in forming a guard to the key, in such a manner as that when it is in the lock on the inside of the door, it cannot be turned by any instrument in the hand of a person outside.

To enable others skilled in the art to which it appertains to make and use my invention, I describe it as follows, viz:

I make the stem, A, of the key without the wing a, the stem being made in the ordinary way, except that at the end it is turned down, to form a small round tenon, as seen at h, fig. 3, and a small groove is turned in said stem, as seen at d, fig. 3. This groove may be about one-eighth or three-sixteenths of an inch long, and about one-thirty-second of an inch deep. In this groove I place a thin strip of suitable metal, bending it around in the groove, so as to form a cylindrical ring, it being cut of the proper length to allow its ends to meet when in the groove, and its exterior surface to be even with the corresponding surface of the stem, as seen at n, Figure 5, and being so made as to allow it to revolve in said groove. I then form the guard C, as shown at Figure 4, with a hole at e, just large enough to slip over the end of the stem A, and fit neatly on the ring in the groove just described, and in the arm or part f of the guard I make a hole, large enough to work neatly and freely on the tenon h, Figure 3. I then enlarge this hole for about two-thirds of the distance through the arm f, as seen in figs. 4 and 5. When this guard is placed on the stem A of the key, its arm e passes on to the cylindrical ring in the groove d, fig. 5, of the stem, and the arm f on to the tenon h at the end of the said stem, this tenon being of such a length as to pass a short distance through the small part of the hole in the arm f, so that it can be riveted on the shoulder of said hole, so as to prevent it from coming off, and yet so as to allow it to revolve freely thereon, (see fig. 5 at i.) The arm e, I solder to the ring n in the groove d. I then neatly plug up the outer end of the hole in the arm f, so as to conceal the riveting of the tenon h, and to make a good finish to the stem A. I then make the wing a of the shape and size desired, and solder it to the stem A, as seen in Figures 1 and 2. The arms e and f of the guard C are of such a length as to allow the part g of the same to just freely pass over the extreme edge of the wing a, leaving no more space between them than is necessary to allow them to pass freely.

It will be seen from the foregoing description, that when the key is made with the guard, as described, and is introduced into the key-hole of its appropriate lock, it will turn therein freely, while the guard is stationary; and if a burglar tries to turn the key by means of nippers, or any kind of tool he may have to operate with from the outside, he will find himself defeated in the attempt, the guard being incapable of turning while in the lock; and if the precaution is taken, when locking the door, to so turn the key as that its wing a will not coincide in position with the guard C, then it cannot be forced out of the lock, and the burglar cannot introduce a key or lock-pick from the outside.

Having thus fully described my invention, what I claim as new, and desire to secure by Letters Patent, is—

The guard C, in combination with the arm f, for closing the key-hole, constructed and attached to the key, substantially as shown and described, and for the purpose specified.

FRANCIS GREENE.
